WILL K. HOLMES, OF TULSA, OKLAHOMA, ASSIGNOR, BY MESNE ASSIGNMENTS, TO THE
TEXAS COMPANY, OF NEW YORK, N. Y., A CORPORATION OF DELAWARE

TREATING HYDROCARBON OILS

Application filed August 13, 1925. Serial No. 49,931.

This invention relates to the conversion of higher boiling hydrocarbons into lower boiling products such as gasoline, naphtha and the like.

It has been sought to carry on the pyrogenic decomposition of hydrocarbon oils by a continuous method of operation in which the oil to be converted is continuously charged to the system. A fundamental defect or limitation of such attempted continuous processes is that it is impossible during a run to effect a clean separation between the unconverted liquid oil and the heavy carbon-forming hydrocarbons and carbon formed in the reaction and, thus, even though tar or residue be withdrawn from the system during a run in a conventional manner, there is a tendency, as the run is continued, toward the concentration of the carbon-forming constituents and carbon which imposes a serious limitation upon the length of runs. In the cracking reaction there are formed, in addition to the lighter hydrocarbons which are ordinarily evolved as a vapor, certain polymerized constituents or heavy hydrocarbons which are readily decomposed to yield free carbon. In the continuous method of operation it is, as stated, practically impossible to remove all of these bodies from the converter by drawing off tar in the conventional manner, due to the difficulty in obtaining complete separation of these bodies from the other liquid oil. The result is that as a run is continued these constituents tend to accumulate in the converter and the heat employed in the cracking operation readily decomposes them into free carbon. As a run is continued there is thus an inevitable tendency toward the accumulation of heavy carbon-forming oils and carbon or coke which necessitates stoppage of the run.

I have found that the length of runs may be materially increased by periodically subjecting the converters to a temporary flushing operation. Thus, by sufficiently increasing the rate of charge to the cracking zone and increasing the amount of tar withdrawn therefrom, the heavy residual products may be readily removed from the system.

In practicing the invention the oil to be

converted is introduced into a converting chamber, or preferably into a series of converters, wherein the oil is maintained under superatmospheric pressure and at a temperature adequate for an efficient rate of cracking. Tar or residue is withdrawn from the converters either practically continuously or intermittently and fresh oil is admitted in substantially a continuous manner so as to maintain a quantity of oil in the converters. It facilitates the removal of tar and contributes to the smooth operation of the process to subject the oil undergoing conversion to agitation or stirring.

Distillate is preferably taken off directly from the converters, although if desired the distilling operation may be carried on separately from the cracking per se by withdrawing liquid containing the lighter hydrocarbons formed and subjecting this liquid to distillation for the recovery of gasoline. As stated, however, it is preferable to carry on distillation concurrently with the cracking operation and it is desirable to produce a suitably fractionated product adapted for the particular grade of gasoline desired without the necessity of having to subsequently distill the distillate obtained from the converters. Suitable fractionating means is, therefore, provided to fractionate the evolved vapors so that a distillate of desired boiling point may be taken off directly from the cracking apparatus.

The operation is thus continued, fresh oil being supplied to the converters and distillate and residue being removed. As the run continues there is a tendency, as heretofore explained, for heavy carbon-forming products to collect in the converters. The accumulation of these heavy bodies may be observed by an increase in the specific gravity of the tar samples withdrawn, by an increase in the amount of power required for operating the stirring or scraping mechanism and by a lowering of the temperature in the bottom of the converters where the heavier products accumulate. This accumulation of heavy bodies in the stills is in some instances perceptible after the stills have been on stream for a few hours but in most cases, if

the conditions which I have found requisite for long running are observed; the phenomenon does not become noticeable until the stills have been on stream for some three or four days or even longer. When it is observed that the liquid in the stills is becoming excessively heavy, the charge of oil to the stills is temporarily increased and increased quantities of liquid are temporarily withdrawn so that the heavy residual products together with any carbon that may have been formed are thoroughly flushed out or removed from the stills.

In carrying on the flushing operation the rate of charge and the rate of withdrawal may be so increased that the cracking operation is for a time suspended or at least the rate of distillate formation reduced; in fact the flushing may be carried out to such an extent as to stop for a time the flow of distillate. In general, however, I do not find it necessary to conduct such an extensive flushing out action and have found in practice that it is possible to carry out the scrubbing or cleaning operation in such a way as to not seriously impede the cracking operation and formation of distillate. Thus for example, when the normal rate of charge is around 40 or 50 barrels per hour, with a converter capacity of some 300 or 400 barrels, the rate during the flushing operation may be increased a few barrels, but usually not over 10 barrels, without reducing the rate of distillate more than 2 or 3 per cent. It is desirable to increase the amount of heating commensurate with the increased charge so as to avoid unduly lowering the temperature of the oil undergoing conversion, whereby the rate of conversion and distillation is not materially reduced.

The flushing operation is carried on for a time until the heavier products have been removed from the system, the operation lasting in some cases only a few minutes but in general, for periods of several hours, for example, five to eight hours. The rate of charge is then dropped back to normal and the rate of tar draw-off reduced so as to maintain the required liquid level in the stills. During the flushing operation the gravity of the tar is ordinarily lighter than that normally drawn off but after the flushing has ceased the gravity is soon normal again and the distillate rate also assumes normal proportions. The regular operation is then resumed until the stills again run heavy when the flushing operation is repeated. Ordinarily it is only necessary to flush at intervals of about three or four days. However, the frequency of the flushing operation, as well as the extent and character of same, depend upon various conditions of operation and more especially upon the character of charging stock employed.

By thus periodically cleaning the stills of

the heavy carbon-forming products it is possible to maintain them on stream for considerable periods of time. Pressure stills may be kept in continuous operation in this manner for several months at a time. So far as I am aware it has been impossible prior to my invention to conduct extended runs of this character.

In the preferred embodiment of the invention the oil to be treated is passed through a coil or heating element of restricted cross section wherein the oil in transit is raised to a cracking temperature, the rate of flow being so regulated that, although the oil is heated to the cracking temperature desired, it is removed from the coil before any material decomposition occurs. The heated oil is discharged into a converter, or preferably a series of converters, wherein quantities of oil are maintained at a cracking temperature under superatmospheric pressure. The oil undergoing conversion is subjected to agitation or stirring which tends to prevent deposition of carbon on the walls of the converters and assists in maintaining the contents in a suitably liquid condition so that the residue may be readily drawn off. In carrying on the flushing operation the rate of charge through the heating coil is increased slightly and preferably also the amount of heat supplied to the coil is increased, while increased quantities of liquid are drawn off from one or more of the converters.

In order to describe the invention more specifically I have, by way of example, shown in the accompanying drawing an apparatus adapted for practicing the invention, the drawing being a diagrammatic sectional elevation.

In the drawing 10 represents a battery of stills consisting of the stills 10a, 10b, 10c, and 10d, interconnected by suitable vapor equalizing lines 11 and liquid level lines 12. The stills are shown mounted in a furnace 13 although, if desired, they may be insulated to retard or prevent loss of heat by radiation, the necessary heat for the cracking operation being supplied by sufficiently heating the oil prior to its introduction to the stills. Each still is provided with a shaft 14 carrying a plurality of scrapers or stirring elements 15 which operate to agitate the contents of the stills and, if desired, to scrape the walls thereof and thus remove any carbon or coke deposited thereon. The shafts 14 are shown connected by cooperating bevel gears 16 to a common shaft 17 which is suitably power driven.

18 represents a coil or conduit of restricted cross section suitably mounted in a furnace 19, the furnace being preferably adapted to heat the oil to a cracking temperature. A pump 20 is adapted to draw oil from a suitable source and force the oil through a

charging line 21 to the heating coil 18. If desired, the oil before being introduced into the coil 18 may be passed through suitable preheaters or economizers heated, for example, by waste heat from the furnace 19, or from the furnace 13, or from both of these furnaces, or by such other heat exchange apparatus as may be desired.

The heating coil is provided with an outlet 22 adapted to conduct the heated oil to one or more of the stills 10. As illustrated the pipe 22 is shown as having valved branches 23 and 24, which branch lines communicate, respectively, with valved branches 25 and 26, and 27 and 28, which lead, respectively, to stills 10a, 10b, 10c, and 10d. By properly manipulating the valves in the lines 23, 24, 25, 26, 27, and 28 it is possible to introduce the charging stock to any or all of the stills as may be desired.

The stills are provided with valved tar lines 29, 30, 31 and 32 which preferably communicate with a common tar line 33. The tar line 33 may, if desired, lead to a suitable exchanger supplied with charging stock by the pipe 21 so that the heat of the tar may be utilized in imparting heat to the charging stock.

The battery of stills is provided with a vapor line 34 that extends to a fractionating tower 35 which may be in the form of a bubble tower, packed tower, or other suitable fractionating column. The fractionating tower 35 is equipped with a vapor line 36 which leads to a reflux condenser 37, a back-trap line 38 being provided for conducting the reflux condensate to the fractionating column 35.

The reflux condenser is equipped with a cooling coil 39 and the cooling medium for the coil is drawn by a valved pipe 40 from the charging line 21 and returned by valved pipe 41 to the charging line. The charging stock may thus be utilized in furnishing the cooling required to supply the fractionating device 35 with the necessary cooling or reflux liquid while at the same time the charge is preheated to a certain extent.

The line 21, intermediate the points of junction of pipes 39 and 40, is provided with a valve 42 so that, if desired, a portion of the charge may be passed directly through the line 21 to the pipe 18 or to such other economizer or preheating apparatus as may be desired, while a certain portion of the charge is by-passed through the line 40, coil 39 and pipe 41. By appropriate manipulation of the valve 42 and the valves in the lines 40 and 41, the amount of charging stock passed through the coil 39 may be accurately regulated to cause such degree of cooling and condensation as to yield a definite quantity of reflux liquid which may be refluxed to the fractionating device by the reflux condensate line 38. In this way it is possible to accurate-

ly regulate the boiling point of the fraction which passes off as a vapor from the reflux condenser 37. A pipe 43 is provided for conducting this vapor to a suitable cooling coil 44, the outlet 45 of which extends to a receiving drum 46 having a gas outlet line 47 and condensate line 48.

The pump 49 illustrated is adapted to return to the heating coil or charging line 21 the hot condensate that collects in the bottom of the fractionating column 35. The pump is equipped with surge lines 50 interposed between the pump cylinder 49 and the valve chambers 51 and adapted to protect the pump piston and packing from the hot liquid. An inflow line 52 extends from the bottom of the fractionating device 35 to branch lines 53 which communicate with the valve chambers 51. The discharge line embraces the branch pipes 54 which extend from the valve chambers to the discharge main 55 that communicates with the charging line 21.

In the preferred method of practicing the invention with the particular apparatus illustrated, the oil to be treated, after having been passed through such heat exchangers and preheaters as may be desired, is introduced to the heating coil 18. The oil in transit through this coil is raised to a cracking temperature and is then passed through the line 22 and its connected branch lines to the battery of stills 10. It is generally preferable to charge the oil into one or more of the stills of the battery and draw tar from the other stills of the battery. Thus with the valve in the line 24 closed and the valve in the line 23 open the heated oil may be passed through the line 23 and its branches to either or both of the stills 10a and 10b. After operating conditions have been established the bulk of the tar removed is drawn through lines 31 and 32 from stills 10c and 10d. Ordinarily, since the oil passes in succession from the charging stills 10a and 10b, first to still 10c and then to still 10d, the tendency is for the oil in the latter still to reach a more advanced stage of decomposition; consequently it is best to remove the bulk of the tar from this still. Tar is removed either by cracking the valves in the lines 31 and 32 for the continuous removal of residue or by "taking shots" from these stills from time to time as may be necessary.

The evolved vapors pass through the line 34 into the fractionating column 35 wherein they are fractionated to the desired degree. The heavier fractions, or those of higher boiling point than desired, are removed from the column 35 by the surge pump 49 and thus returned to the cracking zone for retreatment. The vapors are conducted by the pipe 36 to the reflux condenser 37 wherein a portion thereof is condensed while the remaining vapors are removed by the vapor line 43 to the condenser coil 44. The charge of oil

being introduced to the system by the pump 20, and such portion of the charge as may be necessary, is by-passed through lines 40 and 41 through the coil 39. It is to be understood that the amount of oil thus passed through the coil 39 is varied during the run as conditions may require so as to control the gravity or boiling point of the fraction removed as a vapor in the line 43 and collected as a condensate or distillate in the receiver 46.

When there is evidence that the oil in the stills, more particularly in stills 10d and 10c, is becoming unduly heavy by reason of the increased concentration of the carbon-forming constituents, as has heretofore been explained, the rate of charge to the heating coil 18 and consequently to the battery 10 is increased and increased quantities of tar or residue are drawn off from the stills.

It is best to determine the gravity at which it is desired to hold the tar regularly withdrawn from the system, this gravity depending upon the particular charging stock employed, the amount of cracking desired, and proportion of distillate to be removed, and the length of run desired. Whenever the gravity becomes unduly heavy, that is, heavier than the limit determined upon, the flushing operation is carried on. As heretofore explained the need for flushing is also shown, when employing stirring, agitating or scraping mechanism in the converters, by an increase in the amount of power required for operating such mechanism. A lowering of the temperature in the bottom of the converters, where the heavy carbon-forming oils and carbon tend to collect, may also indicate the need for flushing. Thus, for example, when the usual operating temperatures in the bottom of the converter are around 760° F. to 800° F., a drop during a run to approximately 720° F., particularly when there is not a corresponding drop in temperature in the other portions of the converter, shows the need for flushing.

In carrying on the flushing operation the oil may be charged into the stills 10a and 10b and residue drawn off from one or both of the stills 10c and 10d. In some cases it is advantageous to charge directly into the still or stills in which the heavy carbon-forming oils have collected. Thus the valve in the line 23 may be closed, the valve in the line 24 opened and the oil passed through the line 24 and its branches into one or both of the stills 10c and 10d, tar being drawn off through lines 31 and 32 as usual. In this way the flushing liquid is conducted directly to the still or stills where it is most needed.

By carefully regulating the temperature in the furnace 19 and the rate of charging it is possible to deliver to the stills or converters 10 oil that has been heated to a cracking temperature without any material de-

composition having taken place. This method of operating keeps the tubular heater 18 substantially free from carbon or coke formations, even though operated for long periods of time. And by periodically flushing out the stills 10, or such of them as may be necessary, not only is the formation of carbon or coke deposits in the converters retarded or prevented but any carbon deposits that are formed may be eliminated. In this way the operation is so conducted that in no part of the apparatus are injurious deposits of coke or carbon formed so that the stills may be kept on stream for extended periods of time. During the flushing periods it is usually desirable to increase the heating somewhat in order that the normal operating temperature and rate of distillation shall not be unduly lowered.

By way of example, it may be stated that runs of several months' duration have been made by using as charging stock gas oil of around 30.0 Beaumé gravity and having a mean boiling point of 580° F.-600° F., or thereabouts, maintaining the outlet of the coil 18 at about 775° F. to 800° F., or somewhat higher, normally holding the stills or converters at about 760° F. to 800° F., using pressures of 200-300 pounds in the stills, taking off distillate approximating 55-65 Beaumé gravity and normally drawing off tar or pressure bottoms of about 16-23 Beaumé gravity, while periodically subjecting the stills to the flushing operation described herein. The tar withdrawn contained only about .25% of free carbon.

The practice of the invention has resulted in reducing the percentage of coke formed per barrel of charge to such an extent as to make possible the extended runs.

Obviously many modifications and variations of the invention, as hereinbefore set forth, may be made without departing from the spirit and scope thereof, and therefore, only such limitations should be imposed as are indicated in the appended claims.

What I claim is:

1. The process of converting high boiling hydrocarbon oils into lower boiling products that comprises passing a stream of oil under pressure through a heating coil and delivering it into an enlarged chamber where cracking, distillation, and carbon deposition are effected, applying heat to the coil to raise the oil in transit to a cracking temperature and maintaining a cracking temperature on the oil in said chamber, normally withdrawing tar from the cracking chamber at a normal rate, temporarily increasing the quantity of oil charged through the coil and increasing the rate of tar withdrawal above the normal rate at such times as the gravity of the oil in the chamber exceeds a predetermined density, and concurrently increasing the application of heat to the coil to substantially 130

maintain the rate of distillation from the chamber and the temperature of the oil emerging from the exit of the coil.

2. The process of converting higher boiling hydrocarbon oils into lower boiling ones that comprises subjecting a body of liquid oil to distillation at cracking temperatures and superatmospheric pressure, normally charging fresh oil to the still and withdrawing tar and distillate under conditions to maintain a given yield of distillate and agitating the body of oil to maintain any carbon formed in suspension in the liquid, periodically subjecting the still to a temporary flushing by increasing the charge above the normal rate and withdrawing increased quantities of tar while continuing the agitation to thereby remove from the still any accumulations of suspended carbon and heavy carbon-forming hydrocarbons, and after each flushing operation restoring approximately the normal rate of charge and tar removal to thereby maintain approximately the given yield of distillate with the still on stream for an extended period of time.

In witness whereof, I have hereunto set my hand this 6th day of August, 1925.

WILL K. HOLMES.
